SCUPPER

Filed Dec. 26, 1929

UNITED STATES PATENT OFFICE

STUART P. MEAD, OF TACOMA, WASHINGTON

SCUPPER

Application filed December 26, 1929. Serial No. 416,672.

This invention relates to improvements in scuppers such as used in connection with all types of ships, for example, war vessels, yachts, houseboats, barges, etc., and it consists of the constructions, combinations and arrangements herein described and claimed.

An object of the invention is to provide a scupper made of yieldable material, for example, molded, reinforced rubber, which, by virtue of the combined qualities of flexibility and toughness, enables the production of such a device at a low cost as well as a more efficient maintenance thereof inasmuch as it will withstand blows with less likelihood of damage either to itself or to the object imparting the blow than would be the case if the scupper were made of metal.

Other objects and advantages will appear in the following specification, reference being had to the accompanying drawing, in which:

Figure 1 is a perspective view illustrating the installation of the improved scupper upon the side plates of a ship.

Fig. 2 is a central longitudinal section illustrating a back check valve used in conjunction with the scupper.

Fig. 3 is a somewhat enlarged sectional view of the scupper particularly illustrating the reinforcement of the rubber.

Fig. 4 is a detail cross-section taken substantially on the line 4-4 of Fig. 1.

Fig. 5 is an elevation of a form of the scupper modified to over-reach an armor belt on the ship.

Fig. 6 is an elevation of a modified form of the scupper assuming the shape of an elbow.

As is commonly known, especially among persons having to do with the management of ships, a scupper is a device or an arrangement of some sort for the purpose of an overboard discharge of water. Scuppers made of metal are known and are in use and by virtue of their outstanding position on the side of the ship are subject to being struck and damaged.

In addition to being heavy, such scuppers are costly to repair, and since these devices are sometimes struck with such force as to

destroy them beyond repair, an ever higher cost is entailed by virtue of the necessity of a complete replacement.

Other disadvantages of metallic scuppers are that a trail of rust will soon appear at the sides and especially below the place of connection with the plates of the ship as well as the possibility of setting up a galvanic action. The unsightliness of streaks of rust, especially on war vessels having a projecting armor belt is apparent enough, and in any case is objectionable because of the discoloration of the side of the ship.

All of the foregoing objections are obviated entirely by making the scupper 1 of a material such as rubber. The scupper comprises a spout 2 and a surrounding flange 3. This flange is continuous and the upper part of it bridges the opening 4, at which the scupper has communication with the outlet side of a casing 5 (Fig. 2) containing a back check valve 6. The inlet side of this casing has connection with a soil pipe 7 in the present instance, but obviously the connection of the scupper may be with anything else.

A rectangular metallic annulus 8 is made to bear against the outside of the flange 3 not only to insure pressing the flange against the side plates 9 of the ship, but also to furnish a sufficiently stout foundation or bearing for the heads of the securing means 10. The securing means may comprise screws or bolts, the preference being optional with the person making the installation.

A reinforcement 11 imparts more strength and toughness to the scupper 1 than the rubber or other yielding material of which it is made possesses. This reinforcement may comprise a wire or cloth insert, a preferred disposition of the reinforcing strands being longitudinally of the spout 2, as clearly designated in Fig. 3, and as also suggested in Fig. 4. These strands may extend into the flange 3 in any appropriate way, but in merging the spout strands with the flange strands of the reinforcement, consideration must be given to the possibility of the spout being struck in almost any lateral direction with a consequent doubling over to a greater or lesser extent.

Assuming the spout to be struck sidewise, it can be understood that the longitudinal strands will bend somewhere along their length, probably at a point near their connection with the flange 3. If the disposition of the strands was other than longitudinal, the yielding thereof with the rubber spout would not be so uniform and natural and the possibility would be that they might fail to 5 function as a reinforcement. The inherent flexibility of the rubber is augmented by the reinforcement rendering it extremely tough and capable of enduring hard use.

Any ordinary blow of sufficient force to 15 severely damage a metallic scupper would merely double the rubber scupper over. An additional advantage of the rubber scupper is that it is non-corrosive. Therefore, it is not subject to rusting and will not set up 20 a galvanic action. Moreover, the rubber scupper does not require painting. A pigment of a color to match that of the ship will be embodied in the rubber in the process of molding the scupper.

25 It is perfectly obvious that a scupper made of the material mentioned will be much lighter than one made of metal. Various shapes will be adopted to suit particular purposes. For example, in Fig. 5, the scupper 1 is particularly shaped to extend well beyond the armor belt 12, while in Fig. 6 it has the form of an elbow which will direct the water in a downward path rather than in a parabolic stream, as in the instance of the spout 2 in 30 Figs. 1 and 2.

The manner of installation of the scupper will be clearly understood from an inspection of Figs. 1 and 2. Originally the flange 3 is imperforate and the requisite holes will be 40 punched where needed when the installation is made. For example, if the fastening means 10 will be employed as the common connectors of the scupper 1 and the valve casing 5 the holes in the flange 3 will be punched at 45 places to agree with the holes in the flange of the valve casing. The same fastening means will then be employed to secure both parts together, but, as already brought out, the annulus 8 will be set on the outside of 50 the flange 3 for the purposes already emphasized.

In conclusion, the employment of rubber or other yielding material makes it possible to 55 extend the scupper 1 farther from the side of the ship than would ordinarily be ventured with metallic scuppers. It has been stated that the danger with the latter is that of breaking when struck by some passing obstruction, as a lighter, float, etc., hence the 60 tendency is to make the scupper as short as possible. However, there are instances when it is desirable to extend the scupper a considerable distance from the side of the ship, and by making it of rubber, the danger of 65 breakage by striking an obstruction need not

be feared because the rubber scupper will instantly return to its original position when the obstruction has passed on.

While the construction and arrangement of the improved scupper is that of a generally preferred form, obviously modifications and changes may be made without departing from the spirit of the invention and the scope of the claims.

I claim:—

1. A scupper comprising a spout of yieldable material, and reinforcing means embodied therein running longitudinally of the spout to harmoniously yield with the spout when struck by an obstruction.

2. A scupper comprising a rubber spout with an entrance opening, a flange made integral with the spout and of the same material having a portion bridging the opening, and yieldable reinforcing means embodied in the scupper, extending longitudinally of the spout and merging into the flange.

3. The combination of a supporting plate, a flanged check valve casing confronting one side of the supporting plate and having a discharge communicating with an opening in the plate, a scupper comprising a spout having a flange confronting the other side of the supporting plate and communicating with said opening, securing means passing through the supporting plate and the flanges of the casing and scupper to provide a common connector, and a metallic annulus facing the outside of the scupper flange providing a foundation for said securing means.

STUART P. MEAD.
